STOOL

Lloyd D. Royal, Wichita Falls, Tex.

Application April 20, 1953, Serial No. 24,570

Term of patent 14 years

(Cl. D15—8)

To all whom it may concern:

Be it known that I, Lloyd D. Royal, a citizen of the United States of America, residing at Wichita Falls, in the county of Wichita and State of Texas, have invented a new, original, and ornamental Design for a Stool, of which the following is a specification, reference being had to the accompanying drawing, forming a part thereof.

Fig. 1 is a perspective view of a stool, showing my new design;

Fig. 2 is a side view thereof; and

Fig. 3 is a sectional view thereof, taken on the line 3—3 of Fig. 2.

I claim:

The ornamental design for a stool, as shown.
LLOYD D. ROYAL
